CLAIM

I claim the ornamental design for a lamp shade, as shown and described.

DESCRIPTION

FIG. 1 is a front perspective view from above of a lamp shade;
FIG. 2 is a front elevation view thereof;
FIG. 3 is a rear elevation view thereof;
FIG. 4 is a left-elevation view thereof, all side views being substantially identical to that shown;
FIG. 5 is a top plan view thereof; and,
FIG. 6 is a bottom plan view thereof.
